COLLAPSIBLE PAPERBOARD HOUSE

Ferdinand Mallgraf, Little Neck, N. Y.

Application October 11, 1938, Serial No. 234,351

5 Claims. (Cl. 119—23)

This invention relates to collapsible paperboard houses, particularly to folding bird-houses, which may be produced in oblique, square or oblong designs, with a plain or ornamental color finish, the 5 houses being collapsible for the convenience of shipping, mailing and storage, and is an improvement over my Patent No. 1,911,702 granted May 30, 1933, upon a similar bird-house.

The main salient feature of the invention is the 10 simplicity of the single cut blank of paperboard or of any non-metallic material, which is easily folded in assembling the house structure, the overlapping flap ends of the side and bottom panels at the rear providing a sturdy, rigid and durable house construction without any corner bracing when interlocked by the three-fold or three-ply tab formation in a close fit into a keeper-slot therewith, either at the upper roof panel, or at the bottom panel, or at both of the upper roof 15 and bottom panels thereof, and further which, if a bird-house, may be secured to a tree, post, wall or the like, by driving a nail through the upper and lower tabs.

Another salient feature of the invention is the 20 adaptability with a slight modification of using the same principle of a cut blank for the folding and interlocking means for box containers, in which the upper interlocking tabs are printed for the chimney, windows and doors printed on the 25 outside panels, these ornamental features printed thereon may be to suit any type or design of house desired. The printed house feature may apply also to the bird-house, but it has been found that plain wood finish colors are best for the exterior panels of the bird-houses, so as to 30 match in with the trees secured to.

Other features of the invention will appear as 35 the description proceeds in the following specification accompanied by the annexed drawings, in which

Figure 1 is a front view in elevation of the 40 bird-house, the sides spreading outwardly and upwardly at an obtuse angle from the bottom plane of the intermediate front panel.

Figure 2 is a vertical cross-sectional view taken 45 on line 2—2 of Figure 1 showing the front panel inclining forwardly and upwardly from the bottom.

Figure 3 is a rear view in elevation of the 50 bird-house as shown in Figure 1.

Figure 4 is a transverse cross-sectional view taken on line 4—4 of Figure 2.

Figure 5 is a perspective view of the knock-down or collapsible house-blank for shipping, 55 mailing or storage.

Figure 6 is an alternative folding operation of the rear end flaps and rear panel.

Figure 7 is a plan view of the cut blank in its 60 open flat stamped position.

Figure 8 is a front view in elevation of a modi-

fication of a box-like bird-house, in place of the oblique design shown in Figure 1.

Figure 9 is a vertical cross-section taken on line 9—9 of Figure 8.

Figure 10 is a plan view on a slightly reduced 5 scale of the cut blank used in the set up of the box-like bird-house shown in Figures 8 and 9.

Figure 11 is a view in perspective showing a box 10 container for candy or any suitable contents.

Referring to the drawings, particularly to the 15 cut blank shown in Figure 7, the numeral 1 designates the intermediate front panel having laterally suitable folding crease lines 2 and 3 interconnecting obliquely to side panels 4 and 5, with bottom edges 4^b and 5^b, the side panels having gable-like apex or vertex portions 6 and 7, respectively. The side panels 4 and 5 have also 20 crease lines 8 and 9 interconnecting to rear end flap sections 10 and 11 having shoulder portions 10^a, 10^b, and 11^a, 11^b, respectively, and upper and lower tabs 12 and 12', 13 and 13', respectively, the tabs being provided with holes 14 and 14' therein. The front panel 1 has transversely a 25 lower horizontal crease line 16 interconnecting to a bottom panel 17 having also a crease line 18 interconnecting to rear panel 19 provided with a shoulder portion 19^a and a tab 20 which has a hole 21 therein. The front panel 1 has also transversely a further horizontal folding crease line 25 interconnecting to a front roof panel 26 having 30 also a similar crease line 27 interconnecting to a rear roof panel 28 which has a crease line 29 interconnecting to the end eave flap section 30 which is provided with a keeper-slot 31. The 35 front panel 1 is further provided with a suitable ingress opening 32 and a small hole 33 through which a perch stick 34 as shown in Figure 1, may be inserted to a similar hole 33' in the side panel 5, so the end of the perch-stick may be near the opening 32 for use of the mother bird to feed 40 the young birds therefrom.

This description of the cut blank as shown in 45 Figure 7, may be applied to Figures 1, 2, 3, 4, and 5, wherein the blank is assembled in a set up for a bird-house. The bottom panel 17 is provided 50 with cut out portions 37 and 38 for drainage purpose, terminating in edges 17^a and 17^b that contact lower edges 4^b and 5^b of the panels 4 and 5, respectively, and the tapering edges 19^b and 19^a fit and contact adjacent the creases 8 and 9 of 55 the side panels, all of which provide a keystone design for the front, side and rear panels. The gable-like portions 6 and 7 at their apex or vertex portions have a cut-out portion 40 for ventilation and also to eliminate a sharp point there- 60 at, so as to allow the gable-roof panels 26 and 28 to be drawn firmly onto the oblique edges or rafters 41 and 41^a of the gable-like portions 6 and 7 and the shoulder portions 10^a, 11^a, 20^a, so the tabs 12, 12' and 20 in their three-fold or ply 65 65

formation, are secured firmly and snugly in a close fit in the keeper-slot 31. The roof panel 26 has cut slits 26^a and 26^b corresponding to the oblique edges 41 and 41^a of the vertex portions 6 and 7 of the side panels 4 and 5, in order to provide the eave portions E on the side of the house.

In Figures 8 and 9, a bird-house is shown embodying the same folding and set-up operations 10 as the bird-house hereinbefore described, in which the same numerals in the description thereof will be primed for similar parts. In Figure 10 the cut blank shows the crease lines 2', 3', 8', and 9' in parallel relation to each other, thereby providing panels with right angle corner portions, thereby allowing square or oblong panels.

Figure 11 shows a candy box similar to the house form shown in Figures 8 and 9 and made from a blank similar to that shown in Figure 10, 20 the tabs 13" and 13'" and the openings 32', 33" and 33'", and 60' being omitted, the tabs 12" and 12'" being printed to resemble the chimney of a house, and the outer surfaces of the panels being printed to show a window W, a door D, and 25 roofing 28'.

It will be understood that in the blank shown in Figure 10 the front, side, rear, top and bottom panels 1', 4, 5', 10' and 11', respectively, have similar folding or crease lines 2', 3', 8', 9', 16', 30 18', 25' and 26', and interlocking tabs 12', 12" and 20', and keeper-slot 31' as the blank shown in Figure 7, are all similar in construction and purpose although the size and shape of each may vary from the bird-house blank shown in Figure 35 7. The crease lines 2, 3, 8, 9, 16, 18, 25 and 26 and those also in prime as hereinbefore described, may be known as scored lines, or as crimp or 40 hinged portions, just so they are folding lines. Suitable means, if so desired, may be used to 45 secure the upper tabs 12, 12' and 20, and the lower tabs 13 and 13' and similar primed tabs of the modifications shown in Figures 8, 9, 10 and 11, for example, the securing of the tab portions has been shown for nailing through the holes 14, 14', 14" and 14''' for securing to the support or place desired for the bird-house.

If desired, an additional slot 60 as shown in the floor panels 17 and 17' in Figures 7 and 10, 50 may or may not be used to insert the tabs 13 and 13' therethrough, and the tab 20 of the panel 19 then assumes the rearward tab in place of the tab 12' of the panel 11, as shown in Figure 6. If the slot 60 as shown tends to weaken the bottom 55 17 and 17' the slot 60 may be reduced in width and also the tabs 13, 13', 13'', and 13''' reduced in width accordingly. It is a matter of preference in folding the end flaps 10, 11 and the rear panel 19 and end flaps 10', 11' and rear panel 19' to suit whichever is preferable.

60 It is to be understood I do not wish to confine myself to any exactness of any detail of shape or design, material or construction, and reserve the right to make any alteration thereof that may come within the spirit of this invention and the following appended claims.

65 Having thus described my invention what I claim as new and desire to secure by Letters Patent, is as follows:

1. A collapsible house structure, comprising a 70 plurality of interconnecting creases and panels forming the front, rear, sides, floor and roof portions of said house structure, said roof portion provided with front and rear gable roof panels,

one of said panels being provided with a keeper-slot, said panels including rear flap ends and a rear panel having tabs overlapping in a three-fold formation and snugly secured into said keeper-slot of one of said gable roof panels thereby 5 providing an assembled house structure without any corner bracing therewith.

2. A collapsible house structure, comprising a front panel provided with a suitable ingress opening, interconnecting to side panels having gable-like apex portions, said side panels having lateral creases interconnecting to end flap sections provided with upper and lower tabs therewith, said front panel having transversely a lower crease interconnecting to a bottom panel which has also 10 transversely a crease interconnecting to a rear panel provided with shoulder portions and a tab therewith, said front panel having transversely an upper crease interconnecting to a front roof panel having also transversely a crease interconnecting to a rear roof panel having a similar 15 crease interconnecting to an end eave flap section, said roof panel and eave flap section provided with a keeper-slot at their interconnecting creased portion, a small hole adjacent said ingress opening of said front panel and a corresponding hole in one of said side panels adjacent thereto whereby a perch-stick may be inserted diagonally through said holes and adjacent said ingress opening, all of said interconnecting panels forming 20 a complete house structure, whereby said end flap sections with their tabs and the rear panel overlap each other in a three-fold formation whereof the tabs are secured in a close fit into said keeper-slot and firmly interlocked therein. 25

3. A collapsible house structure, comprising a plurality of interconnecting creases and panels forming the front, rear, sides, roof and floor panels of said house structure, one of said roof panels provided with a keeper-slot, said interconnecting 30 panels including rear flap ends and a rear panel having shoulder portions and tabs laminated in a three-fold formation firmly interlocked and 35 snugly secured in a close fit into said keeper-slot of the top roof panel.

4. A collapsible house structure of the character described as defined in claim 1, said front, side and rear panels being of an oblique design whereby said interconnecting creases of said panels diverge upwardly at an obtuse angle from the bottom plane of the intermediate front panel. 50

5. A blank having a plurality of parts associated with each other by creases, said parts including elements that constitute a floor, a roof, and walls of a house structure when said parts are turned on their creases, the roof elements including parts that form front and rear gable roof panels and a keeper-slot in one of them, said elements including an element that forms the front wall, two side-wall-forming elements associated by creases with the front-wall-forming element, a bottom-forming element associated by a crease with the front-wall-forming element, and a rear-wall-forming element associated by a crease with the bottom-forming element, the blank also including rear flap ends, each associated by a crease with one of the side-wall forming elements, the rear-wall-forming elements and the rear flap ends having integral tabs so constructed that, when the blank is bent to form a house, said tabs will overlap and fit tightly into said keeper-slot. 60

FERDINAND MALLGRAF.
